CLAIM

The ornamental design for a paper holder, as shown and described.

DESCRIPTION

FIG. 1 is a front view of the paper holder showing my new design;

FIG. 2 is a bottom plan view of the paper holder;

FIG. 3 is a top plan view of the paper holder;

FIG. 4 is a right side view of the paper holder, showing a paper retention slot in the side of the holder;

FIG. 5 is a right side perspective view of the paper holder; FIG. 6 is a left side perspective view of the paper holder; and,

FIG. 7 is a second right side perspective view of the paper holder, the piece of paper depicted by means of broken lines being shown for illustrative purposes only and forming no part of the claimed design.
